W. F. HAACK

LEAD PENCIL

Filed Jan. 12, 1922

INVENTOR.
William F. Haack
BY *Samuel N. Pond*
ATTORNEY.

UNITED STATES PATENT OFFICE.

WILLIAM F. HAACK, OF BERWYN, ILLINOIS.

LEAD PENCIL.

Application filed January 12, 1922. Serial No. 528,602.

To all whom it may concern:

Be it known that I, WILLIAM F. HAACK, a citizen of the United States, residing at Berwyn, in the county of Cook and State of Illinois, have invented certain new and useful Improvements in Lead Pencils, of which the following is a specification.

This invention relates to lead pencils of the magazine type, which contain a central chamber in which the working lead is held and through which it is advanced by a plunger or pusher as the point of the lead wears away, and a magazine containing additional leads which are successively supplied, as required, to the central chamber.

In an application filed concurrently herewith, Serial No. 528,601, I have disclosed and claimed a magazine lead pencil of the same general type and embodying the same broad structural features that are included in the present invention. In that application I have disclosed a cylindrical shell, which is preferably of a diaphanous or translucent material to enable the interior parts of the pencil to be visible, a single compartmental magazine located in the upper portion of the shell, a central working chamber in the lower portion of the shell beneath the magazine to hold the working lead, a rotatable valve for controlling the passage of the spare leads from the magazine to the working chamber, and a plunger for forcing the working lead endwise through the working chamber and the tip of the pencil. My present invention includes all of the above features, but has been designed as an improvement upon the pencil of the aforesaid companion application mainly in the direction of providing greater storage capacity for the spare leads; this being accomplished in my present invention by the provision of a second compartmental magazine located beneath the upper compartmental magazine and receiving leads from the latter as the leads from the second or lower magazine are successively delivered to the working chamber of the pencil.

My present invention also includes other minor structural features which will hereinafter appear, and which are particularly adapted to a pencil having a plurality of spare lead magazines.

Other objects and attendant advantages of the invention will be apparent to persons skilled in the art as the same becomes bet-

ter understood by reference to the following detailed description, taken in connection with the accompanying drawing wherein I have illustrated one practical and workable embodiment of the invention and in which,—

Figure 1 is a longitudinal axial section, showing both magazines loaded and the plunger or pusher at its maximum point of advancement;

Fig. 2 is a view similar to Fig. 1, but showing the plunger or pusher fully withdrawn, and one of the reserve leads from the lower magazine partially entered within the working chamber, this latter operation being effected by holding the pencil in a horizontal position;

Figs. 3, 4 and 5 are cross sections taken on the lines 3—3, 4—4 and 5—5, respectively, of Fig. 1;

Fig. 6 is a fragmental longitudinal section of the working chamber and the surrounding metal tip or ferrule showing the position of the lead retaining spring in the empty working chamber.

Fig. 7 is a fragmentary longitudinal section taken on the line 7—7 of Fig. 3.

Referring to the drawing, B designates the cylindrical body or shell of the pencil, which is made of any suitable diaphanous or translucent material which will enable the interior parts to be observed through the same. The inner wall of the shell B is formed with a group of spaced longitudinal grooves or channels A extending the full length thereof, said grooves or channels constituting lead holding cells of a pair of upper and lower magazines. The leads C are shown as occupying the cells A, and the leads of the upper magazine are confined laterally within their respective cells by a cylinder T located coaxially within the shell B and of a length approximately one-half the length of the shell.

The leads in the cells of the lower magazine are likewise confined laterally by a longitudinally split cylinder V of the same diameter as, and directly beneath, the cylinder T. The meeting ends of the magazine cylinders T and V are united by an external sleeve or collar Q, which has the additional function of a valve as hereinafter explained. Located within the lower magazine cylinder V is a central chamber D for the working lead. This working chamber is of substantially U form in cross section, as shown in

Fig. 4, and its side walls are united to inwardly turned lips or flanges on the longitudinal margins of the split cylinder V, so that the working chamber D constitutes virtually a re-entrant portion of the magazine cylinder V. The lower end of the lower magazine cylinder V is attached to and centered by a disc G which abuts against the lower end of the shell B and forms a bottom rest for the leads in the lower magazine, as clearly shown in Figs. 1 and 2. Continuous with the working chamber D is a narrowed substantially cylindrical extension D' which guides and supports the lower portion 10 of the working lead and is formed with a narrow longitudinal slot for a purpose hereinafter disclosed. The lower end of the extension D' is secured by soldering or otherwise to the lower end of the tapered tip of a metal ferrule E that is rotatably fitted on the lower end of the shell B.

Frictionally mounted on the working chamber extension D' is a spring collar R, depending from which is a leaf spring R' that, when the working chamber is emptied, 25 springs through the narrow slot in the member D' and closes the latter as clearly shown in Fig. 6. When, however, the lead is forced downward through the working chamber, its point J forces the spring R' outwardly, and the latter, by reason of its frictional grip or drag on the lead prevents the latter 30 from falling out of the pencil. This lead retaining device is identical with the lead retaining device shown and claimed in my aforesaid companion application.

H designates a plunger or pusher having at its upper end a spiral H' that co-operates 40 with a tube K formed with an internal spiral or screw thread fitting the spiral H' of the plunger. The upper end of the spiral tube K is united to a cap L sleeved on the body or shell B by being soldered to the cap L at O, and centered and supported by a disc 45 or spider M. The cap L is longitudinally slit at diametrically opposite points, as shown at L' in Fig. 2, to permit its application and withdrawal.

Near its lower end the plunger H is 50 formed with a pair of lateral lugs S (Figs. 1, 2 and 4), which, by contact with the side walls of the working chamber D, hold the plunger against rotation on its longitudinal axis when the cap L and spiral tube K are rotated to advance or retract the plunger. The lower end of the plunger is further provided with a depending finger P which, after 55 the lead has dropped into the working chamber and is fully centered within the latter, overlaps the upper end of the lead and prevents it from tilting out of engagement with the plunger.

The sleeve or collar Q is formed with a vertical slot U, shown in Fig. 3, through 60 which the leads in the upper magazine are

passed into the lower magazine before their introduction to the working chamber.

Briefly describing the manner of loading and manipulating the pencil, and assuming that both magazines are empty, the cap L with its attached tube K and plunger H are withdrawn from the shell, and the several compartments or cells of the upper magazine are loaded with leads. The tip ferrule E is then rotated on the shell B 70 which carries the slot or port U of the valve Q successively into register with the lower ends of the leads in the upper magazine, so that the latter successively drop into the cells of the lower magazine and fill the latter. The cells of the upper magazine are then filled through the upper end of the shell, and the cap, plunger and plunger operating tube are then re-applied. The pencil is then held horizontal, and the working 80 chamber D is rotated by turning the ferrule E until its entrance channel is uppermost and registers with one of the cells of the lower magazine, whereupon the lead in said cell drops into the working chamber, 90 this being indicated in Fig. 2. By turning the cap L in the proper direction, the plunger is advanced into engagement with the upper or inner end of the lead, with the finger P overlapping its upper end and preventing it from dropping back out of the working chamber. As the point of the lead wears away, the lead is gradually fed forward by the plunger.

When the next lead is required, with the pencil held horizontal the working chamber is brought into register with the next cell of the lower magazine and the lead thereof follows into the working chamber. This brings the previously emptied cell into register with a loaded cell of the upper magazine through the port U of the valve, so that the lead in the upper magazine drops into the lower magazine. In this way, as fast as the leads in the lower magazine are used up, the cells of the lower magazine are re-filled from the upper magazine, so long as leads are left in the latter. Ordinarily the upper magazine will be reloaded as soon as it is emptied, which condition is 105 readily observable through the diaphanous shell of the pencil; but, of course, both magazines can be entirely emptied before re-loading, if desired.

A leading advantage of my present invention, which also inheres in the invention forming the subject matter of the companion application above identified resides in the translucent character of the shell, in combination with a working chamber and two 115 magazines so co-ordinated and related that under a relative turning movement, the reserve leads in the upper magazine can be fed one at a time into the lower magazine, while the leads from the latter are being 120

fed to the working chamber, the manipulation of the parts being observable through the translucent shell. Manifestly the specific details herein shown and described for purposes of illustration may be variously modified without altering the substantial character of the invention or sacrificing any of the advantages thereof. Hence, I reserve all such variations and modifications as fall within the spirit and purview of the appended claims.

I claim—

1. In a magazine pencil, the combination of a cylindrical shell, upper and lower magazines for holding leads in said shell, a working chamber within said lower magazine adapted to receive the leads successively from the latter, means for controlling the passage of leads from said upper magazine to said lower magazine, and means for forcing a lead endwise through said working chamber.
2. In a magazine pencil, the combination of a diaphanous cylindrical shell, upper and lower compartmental magazines for holding leads in said shell, a working chamber within said lower magazine adapted to receive the leads successively from the latter, a rotatable valve controlling the passage of leads from said upper magazine to said lower magazine, and means for forcing a lead endwise through said working chamber.

3. In a magazine pencil, the combination of a cylindrical shell longitudinally channeled on its inner surface to form magazine cells for leads, an inner tube constituting a guard for the open sides of said cells and forming with the latter a compartmental magazine, a rotatable valve member forming a rest for the leads in said magazine and provided with an opening for the passage of the leads therethrough, a working chamber beneath said valve member adapted to receive the leads passed through the latter, and means for forcing a lead endwise through said working chamber.

4. In a magazine pencil, the combination of a cylindrical shell longitudinally channeled on its inner surface throughout its full length to form magazine cells for leads, upper and lower inner tubes constituting guards for the open sides of said cells and forming with the latter upper and lower compartmental magazines, said lower tube having a longitudinal slot, a rotatable valve member connecting the meeting ends of said tubes and provided with an opening for the passage of leads from the upper to the lower magazine, a working chamber within said lower tube having an entrance way for leads registering with the slot of said lower tube, and means for forcing a lead endwise through said working chamber.

WILLIAM F. HAACK.
